ATTORNEY

UNITED STATES PATENT OFFICE.

CLYDE NELSON GRIFFITH, OF NEW CASTLE, PENNSYLVANIA.

SLIDING-JAW WRENCH.

1,100,479.

Specification of Letters Patent. Patented June 16, 1914.

Application filed September 30, 1913. Serial No. 792,656.

To all whom it may concern:

Be it known that I, CLYDE NELSON GRIFFITH, a citizen of the United States of America, residing at New Castle, in the county of Lawrence and State of Pennsylvania, have invented certain new and useful Improvements in Sliding-Jaw Wrenches, of which the following is a specification, reference being had therein to the accompanying drawing.

This invention relates to sliding jaw wrenches, and has for its object to provide a tool of such class in a manner as herein-after set forth, with means for locking the 15 slidable jaw in its adjusted position and for quickly releasing said jaw when occasion so requires.

Further objects of the invention are to provide a sliding jaw wrench which is simple in its construction and arrangement, 20 strong, durable, efficient and convenient in its use, readily set up and comparatively inexpensive to manufacture.

With the foregoing and other objects in view, the invention consists of the novel construction, combination and arrangement of parts as hereinafter more specifically described and illustrated in the accompanying drawings wherein is shown an embodiment 30 of the invention, but it is to be understood that changes, variations and modifications can be resorted to which come within the scope of the claim hereunto appended.

In the drawing, wherein like reference 35 characters denote corresponding parts throughout the several views:—Figure 1 is a side elevation of a slidable jaw wrench in accordance with this invention, Fig. 2 is a sectional elevation, Fig. 3 is a section on line X—X Fig. 2, and Fig. 4 is a section on Y—Y Fig. 2.

Referring to the drawings in detail, the wrench shank consists of a pair of spaced rectangular bars 5 and 6 having fixed to 45 their outer end a jaw 7. Arranged between the bars 5 and 6 is a rotatable locking member including a pintle 8 journaled in the face of the jaw 7, and said locking member further includes a rectangular intermediate 50 portion 9 having the side edges toothed as at 10 and said member further includes a cylindrical rear portion 11 having a reduced end 12, provided with an opening 13 through

which extends a pin 14. The cylindrical rear portion 11 of the locking member is 55 provided with a peripheral collar 15 which extends into grooves 16 formed in the opposing edges of the bars 5 and 6.

The reference character 17 denotes an adjustable and sliding jaw which is provided 60 with a pair of channels 18 and 19 through which extends the bars 5 and 6 whereby the jaw 17 is slidably connected to said bars. The jaw 17 between the channels 18, is formed with a rectangular opening 20 having 65 the side walls thereof grooved and provided with teeth 21 with which engage the teeth 10 whereby the jaw 17 is locked in its adjusted position.

Mounted upon the bars 5 and 6 and the 70 cylindrical portion 11 of the locking member is a handle formed of two sections 22 and 23. The inner face of each of the sections is grooved as at 24 and into which extends the collar 15. The section 23 is provided with an opening 25, through which extends the rear end of the cylindrical portion 11 of the locking member. The bars 5 and 6 are housed within the section 23 and the latter is connected to the bars 5 and 6 75 80 and section 22 by transversely extending rivets 26.

What I claim is:—

A sliding jaw wrench comprising a shank 85 formed of a pair of spaced bars, a jaw fixed to the outer ends of said bars, a handle secured to the rear ends of said bars, an adjustable jaw mounted upon said bars and provided with teeth, a rotatable locking member arranged between said bars and 90 journaled at its outer end in said fixed jaw and having its inner end projecting through said handle, said locking member provided with teeth and engaging with the teeth of the adjustable jaw to arrest sliding movement of the latter, said locking member further provided with a peripheral collar extending into said bars and handle, and a pin carried by the rear end of said locking member. 95

In testimony whereof I affix my signature in the presence of two witnesses.

CLYDE NELSON GRIFFITH.
